CLAIM

The ornamental design for an indexable drill insert for machine tools for metalworking, as shown and described.

DESCRIPTION

1. Indexable drill insert for machine tools for metalworking
FIG. 1.1 is a perspective view of an indexable drill insert for machine tools for metalworking showing our new design;
FIG. 1.2 is a front elevation view thereof;
FIG. 1.3 is a back elevation view thereof;
FIG. 1.4 is a top plan view thereof;
FIG. 1.5 is a bottom plan view thereof;
FIG. 1.6 is a left-side view thereof; and
FIG. 1.7 is a right-side view thereof.

1 Claim, 7 Drawing Sheets
